UNITED STATES PATENT OFFICE.

MYRON T. BALDWIN, OF LA GRANGE, ILLINOIS.

INFANT'S POSING-CHAIR.

SPECIFICATION forming part of Letters Patent No. 321,076, dated June 30, 1885.

Application filed December 10, 1884. (No model.)

To all whom it may concern:

Be it known that I, MYRON T. BALDWIN, a citizen of the United States, residing at La Grange, in the county of Cook and State of Illinois, have invented certain new and useful Improvements in Infants' Posing-Chairs; and I do declare the following to be a full, clear, and exact description of the invention, such as will enable others skilled in the art to 5 10 15 20 25 30 35 40 45 50 55 60 65 70 75 80 85 90 95 100 which it appertains to make and use the same, reference being had to the accompanying drawings, and to the letters and figures of reference marked thereon, which form a part of this specification.

My invention is designed to supply a seat or chair in which an infant may be placed and held in a desired position, and which, while occupied, is invisible in a front view. It is especially useful as a photographer's posing-chair, securing comfort and grace to the sitter and greatly diminishing the artist's labors.

The invention is fully illustrated in the accompanying drawings, in which Figure 1 shows it in side elevation. Fig. 2 is the invention in rear elevation. Fig. 3 is an enlarged sectional view of the clamp or lock, and Fig. 4 is an enlarged plan view of the part of the tilting mechanism attached to the bottom of the chair-seat.

The various parts of the chair are referred to by letters, similar letters indicating corresponding parts in the different views.

The letter A indicates the base of the chair. It is adapted to rest on another chair or elsewhere, as desired. To the top of this base is secured a metal plate, B, having the vertical posts b b supporting the cross-bar b'. The plate B with the posts and cross-bar are preferably cast in one piece, and suitable screw-

holes are made through the plate, so that it can be screwed firmly upon the base A. A threaded hole, a, is made horizontally through a post, b, which admits a thumb-screw, a'.

Represents the seat of the chair, upholstered as desired, and having the back C.

A plate, D, (see Fig. 4,) having sockets d d, in which the ends of the bar b' rest, and a vertical arch, E, are secured to the under side of the seat C by means of the screw-holes

d' d' and common screws. The arch E is furnished with notches e e to receive the point of the screw a'. By this device the chair acquires a tilting motion backward or forward, and is held at any point by tightening the thumb-screw a'. I do not limit myself to this particular device, but use any suitable means for tilting and locking the chair.

In the back C' of the chair I form an oblong vertical opening, c, and attach a wire spring-clamp, F, to the chair-back, as seen in Fig. 2. By passing a handkerchief around the child's body and forcing the ends between the vertical wires of this spring, the child is held firmly in an upright posture. A part 65 of the child's garments may be thus utilized and the handkerchief be dispensed with.

G is a head-rest whose supporting-rod g, bent as shown in the drawings, passes down between the plates H I, of which one, H, has a central threaded stem, h, and is firmly secured to the chair-back C'. The other plate, I, has a central opening to admit the stem h, and also has the recesses i i to receive the rod g. By tightening the thumb-nut K on the 75 stem h, the rod g is firmly held in position.

My chair and its appurtenances, as thus described, are, with a proper arrangement of the sitter's drapery, invisible in a front view, and thus any preferred accessories or objects may 80 be introduced in the picture which would not harmonize with a chair. When desired, however, I attach removable arm-rests L to either side or both sides of the chair. The rest L is attached to the chair by means of a rod, l, 85 which, being fixed to the arm-rest, extends downward behind the chair and into a clamping device similar to that described as holding the head-rest by which it is kept in position.

Having now described my invention, what I claim, and desire to secure by Letters Patent of the United States, is —

1. In a tiltable posing-chair, the combination, with a legless base, A, of a plate, B, having supports b b and cross-bar b', a plate, D, having sockets d d, and arch E, with notches e e, and screw-holes d' d', the threaded hole a, thumb-screw a', and chair-seat C, substantially as set forth.

2. In combination with a posing-chair having a seat, C, the back C', provided with an opening, e, and the spring-clamp F, as herein described.
- 5 3. In combination with a posing-chair, the removable arm-rest L and rod l, and a clamp formed of a base-plate, H, having a threaded stem, h, a plate, I, having recesses i i, and a thumb-nut, K, as herein set forth.

In testimony whereof I affix my signature in the presence of two witnesses.

MYRON T. BALDWIN.
